UNITED STATES PATENT OFFICE.

LOUIS SANDERS, OF NEW YORK, N. Y.

DESIGN FOR A BELT.

SPECIFICATION forming part of Design No. 32,841, dated June 12, 1900.

Application filed May 16, 1900. Serial No. 16,932. Term of patent 3½ years.

To all whom it may concern:

Be it known that I, LOUIS SANDERS, a citizen of the United States, and a resident of the city of New York, borough of Brooklyn, in the county of Kings and State of New York, have invented and produced a new and original Design for a Belt, of which the following is a specification, reference being had to the accompanying drawing, forming a part there-
of, in which is represented a front elevation
of a belt embodying the features of my design.

The leading feature of the design consists in the peaked frontispiece A, appearing to connect the terminals of a back section B and
the ring or chain ornamentation C at the front
of the frontispiece.

In the detail of the design the back section B appears with terminals which rest upon the frontispieces A, the upper edge of which

is concaved at the center, the central portion 20
of the lower edge being convexed. Rings ap-
pearing as portions of the terminals of the
back section rest upon the outer face of the
frontispiece, and a chain which connects the
rings appears as a pendent member. 25

Having thus described my invention, I
claim as new and desire to secure by Letters
Patent--

The design for a belt herein shown and de-
scribed.

In testimony whereof I have signed my
name to this specification in the presence of
two subscribing witnesses. 30

LOUIS SANDERS.
